UNITED STATES PATENT OFFICE.

EDWIN G. NICEWANER, OF JOHNSTOWN, PENNSYLVANIA, ASSIGNOR TO THE LORAIN STEEL COMPANY, OF PENNSYLVANIA.

ATTACHMENT FOR CAR-TRUCKS.

SPECIFICATION forming part of Letters Patent No. 633,727, dated September 26, 1899.

Application filed August 17, 1899. Serial No. 727,494. (No model.)

To all whom it may concern:

Be it known that I, EDWIN G. NICEWANER, of Johnstown, in the county of Cambria and State of Pennsylvania, have invented a new and useful Improvement in Attachments for Car-Trucks, of which the following is a full, clear, and exact description, reference being had to the accompanying drawings, which form a part of this specification.

- 10 This invention has relation to an attachment for car-trucks, and particularly for trucks of the class generally known as "maximum-traction" trucks. In this class of trucks, in which the center of movement is brought up as closely as possible to the driving-axle in order to concentrate to a greater or less degree the weight or load upon such axle, the resulting increased distance of the rear wheels or trailers from the center of movement and 15 the corresponding increase in radial movement thereof generally requires these wheels to be made of comparatively small diameter in order to permit them to cut under the sills and steps of the car in turning sharp curves. 20 This reduction in diameter of these wheels and the comparatively light weight which they carry give them a tendency, especially on curves, to climb the rails or "jump the tracks." This is a well-known objection to 25 trucks of this type, and various means have heretofore been provided to obviate it, but have for the most part and for various reasons proved undesirable or impracticable under the conditions of actual practice. 30 It is the object of the present invention to provide means of this character which can be readily applied to various types of this class of trucks for the purpose of overcoming the objection above described in a simple, efficient, and satisfactory manner; and with this object in view the invention consists, generally considered, in the provision of a spring seated upon the truck-frame adjacent to the trailer-wheels of the truck, in combination 35 with means actuated by the radial movement of the truck in either direction for putting said spring under compression to a degree corresponding to the degree of movement of the truck, and thereby oppose its action to

the tendency of the wheels to climb or jump 50 the rails.

The invention also includes means in connection with the means above generally stated for permitting automatic adjustment of the latter to compensate for changes in the relative positions of the car body and truck under various running conditions. 55

It also consists in the novel construction and combination of parts hereinafter described, and pointed out in the claims, reference being had to the accompanying drawings, in which—

Figure 1 is a plan view of a car-truck and a portion of a car-body, illustrating the application of the invention. Fig. 2 is a side view 65 of the same. Figs. 3 and 4 are detail views. Fig. 5 is a plan view showing the invention, and Fig. 6 is a side elevation.

In the drawings the letter A designates one of the large wheels of the truck mounted on 70 the driving-axle, B one of the smaller or trailer wheels, and C a cross bar or brace of the truck-frame.

D is one of the cross-sills of the car-body, and E a portion of the car-floor. 75

F F designate two segment rack-plates, which are rigidly secured to the under side of the car-body at its central portion and are of a curvature corresponding to the radius of movement of that portion of the truck immediately beneath them. 80

G is a pinion which is rigidly secured on the upper end portion of a vertical rod or shaft G' between the two rack-plates, the relative position of said plates to each other and to 85 the pinion being such (see Fig. 5) that under normal conditions the center line of the pinion coincides with the center of the first tooth on both racks, whereby as the pinion becomes operatively engaged with one rack it passes 90 out of engagement with the opposing rack.

H is a stiff coiled spring which is seated in a pocket of the casing I, which in the present instance is shown as secured to the bar C of the truck-frame, with its vertical center coinciding with the center of the pinion G and rod or shaft G'. 95

J is a nut or follower seated on the upper

end of said spring and also on a threaded portion G^2 of the rod or shaft G' , being prevented from turning in the latter by means of lateral lugs or projections J , which engage vertical 5 grooves i in the walls of the spring-pocket I .

In order to guard against any injury to the parts by reason of changes in the relative positions of the car body and truck due to variations in the height of the two track-rails 10 or to lateral oscillations of the car-body, the casting which carries the spring-pocket is pivotally connected to the bar C by means of a stud or trunnion M , which extends loosely through a bearing in said bar.

15 m is a washer, and m' is a nut for securing the stud in its bearings.

M' is a second and opposite trunnion, having its bearings in a bracket M^2 , secured to the truck-frame. These, however, are mere details 20 of construction, which may be changed at the pleasure of the designer and builder, it being essential only that means of proper character shall be provided to permit the rod or shaft G' , with its pinion G , to automatically adjust 25 itself to compensate for the relative movements of the car body and truck, as described. The upper end of the said rod or shaft is centered by means of a swiveled antifriction-wheel P , which runs in the groove of a channelled bearing-plate B , secured to the under 30 side of the car-floor.

The operation of the device will be readily understood from the foregoing. As the truck radiates under the car-body in either direction 35 the pinion G is caused to engage with the corresponding rack-plate and, together with the rod or shaft G' , is rotated thereby, moving the nut or follower J down against the spring and compressing the latter to a degree 40 in proportion to the radial movement of the truck and opposing its resistance to the tendency of the trailer-wheels to leave the track. When the body and truck resume their normal relations, the pinion is rotated in the reverse 45 direction and the spring gradually relieved of compression. Inasmuch as the two racks engage opposite sides of the pinion, the action is the same under radial movement of the truck in both directions. It will also be noted that the nut or follower J will readily 50 adjust itself on the spring under different conditions of load.

By the means described I not only overcome 55 in a satisfactory manner the objection noted at the outset, but I enable the diameter of the trailer-wheels to be considerably reduced, so as to work under a much lower car-body than has heretofore been possible.

While I have shown the device applied in 60 front of the trailer-wheels, it is obvious that it may be applied over the axles thereof or to the rear thereof by providing the truck-frame with a proper brake or cross-bar to receive the spring-pocket. The particular location 65 in each case will largely depend upon the particular style of truck to which the invention

is applied, the fancy of the builder, or the necessity for avoiding conflict with the brake-rigging or other adjuncts of the particular truck, nor do I wish to limit myself in other respects to the particular embodiment of the invention which I have herein shown and described, as various mechanical changes may be made without departing from the invention as set forth in the appended claims.

Having thus described my invention, what I claim, and desire to protect by Letters Patent, is—

1. The combination with a car-truck, and a spring arranged to oppose its resistance to vertical movement, of an axle of said truck, of a nut or follower arranged to act on said spring, a screw engaging said nut to effect longitudinal movement thereof toward and away from the said spring, and means whereby 85 said screw is actuated by radial movement of the truck.

2. The combination with a car-truck, and a spring arranged to oppose its resistance to vertical movement of an axle of said truck, of a nut or follower against which one end of said spring is seated, a rod or shaft having a screw-thread engaging said nut or follower, means for preventing rotary movement of the nut or follower, a pinion on said rod or shaft and segment-gears secured to the car-body and engaging the said pinions.

3. The combination with a car-truck, and a spring arranged to oppose its resistance to vertical movement of an axle of said truck, of a nut or follower against which one end of said spring is seated, a rod or shaft having a screw-thread engaging said nut or follower, a pinion on said shaft and segment-gears secured to the car-body and engaging the said pinion, together with means for retaining the engagement of said gears and pinions under changes in the vertical relation of the car body and truck.

4. The combination with a truck-frame having a spring-pocket secured thereto and provided with vertical grooves in its walls, a spring seated against the bottom of said pocket, a nut seated in said pocket against the opposite end of said spring and having 115 projections engaging said grooves, a rod or shaft having a thread engaging said nut and also carrying a pinion, and segment-gears secured to the car-body and engaging opposite sides of the said pinion.

5. The combination with a car-truck of the character described, and with the car-body, of a spring-pocket pivotally secured to the truck-frame, a spring seated in said pocket, a nut bearing against the said spring, means 125 for preventing rotation of the said nut, a rod or shaft having a thread which engages the said nut, a pinion on the said rod or shaft, segment-gears on the car-body engaging the said pinion, and a guide-bearing for the upper end of said rod or shaft.

6. The combination with a car-truck and a

- car-body, of a spring bearing on the truck-frame, a nut bearing on the said spring, a rod or shaft engaging the said nut to impart reciprocating movement thereto, a pinion on the said rod, segment-gears secured to the car-body, and engaging the said pinion, a swiveled antifriction-wheel at the upper end of said rod, and a guide-plate for said wheel on the car-body.
- 5 7. The combination with a car-truck and a car-body, of a spring bearing on the truck-frame, a nut bearing on the said spring and held against rotary movement, a shaft for actuating said nut, a pinion on the said shaft, and segment-gears engaging opposite sides of 15 the said pinion and having normally the center lines of their first teeth coinciding with the center lines of said pinion.
- 10 In testimony whereof I have affixed my signature in presence of two witnesses.

E. G. NICEWANER.
